UNITED STATES PATENT OFFICE.

OTIS A. MYGATT, OF NEW YORK, N. Y.

PRISMATIC-GLASS REFLECTOR.

No. 821,811.

Specification of Letters Patent.

Patented May 22, 1906.

Application filed January 11, 1906. Serial No. 295,657.

To all whom it may concern:

Be it known that I, OTIS A. MYGATT, a citizen of the United States, residing at New York, in the county of New York and State of New York, have invented certain new and useful Improvements in Prismatic-Glass Reflectors, of which the following is a specification, reference being had therein to the accompanying drawings.

10 This invention relates to reflectors composed of prismatic glass and to the combination of such reflectors with artificial lights in a peculiar manner.

15 The object of the invention is to produce a reflector of prismatic glass which shall be substantially free from deterioration by the accumulation of dust and which may be available for use either with a single light or with a cluster of lights and with or without auxiliary 20 reflectors.

Reflectors composed of prismatic glass are well known and have many advantages over metallic reflectors in that they are usually more brilliant and of less cost. One of the 25 principal objections to a reflector of prismatic glass, however, is that when dust accumulates on the prismatic surface thereof it cannot be readily removed and frequently acts to diminish the efficiency of the reflector. In 30 my present invention I so arrange the prismatic surface that the presence of dust thereon does not diminish the reflecting power of the reflector.

Figure 1 is a side elevation of a reflector according to this invention arranged with relation to a cluster of incandescent electric lamps. Fig. 2 is a partial elevation and partial section of a similar reflector with incandescent lamps and attachments arranged in 40 different relation thereto, some lamps having auxiliary reflectors. Fig. 3 is a cross-section on line 3 3, Fig. 1.

In my Patent No. 763,689, of June 28, 1904, I show and describe a reflector composed of 45 prismatic glass and having its reflecting-prisms disposed on the exterior of the frustum of a spherical or spheroidal body, the interior of said body having the reflecting-face, although the actual reflecting-surfaces are the planes of 50 the prisms at the opposite face of the glass. The theory of light reflection is pretty fully set forth in said patent. In the present invention the light-reflecting prisms are arranged in the interior of a frusto-conical or 55 approximately such shaped body instead of on the exterior, as in the patent referred to.

The prisms are of the general character of the reflecting-prisms described in said patent; but being in the interior instead of on the exterior of a curve the reflector-prisms have a 60 tendency to diffuse rather than to concentrate rays of light.

The letter A represents a body of clear glass, usually made by pressure in a mold. The outer surface of this body is smooth and 65 preferably fire-polished. The body shown is a modification of the conic frustum with the base at the upper end. The convex outer surface is smooth. The interior or concave surface of the body A is substantially covered 70 with light-reflecting prisms B. These prisms are of the general character of reflecting-prisms described in said patent.

When the reflector is used for a cluster of lights, it is suspended, as shown in Figs. 1 and 75 2. Lights C C may be arranged to radiate from a center below the reflector and will be covered by the flared portion of the reflector. The dust which accumulates on the upper surface of the prisms B does not interfere with 80 their reflecting power. Dust will not accumulate to a great extent on the lower or convex surface of body A, and what does so accumulate is readily accessible and may be wiped away. The lights C are largely protected against dust by the overhang of the flared portion of the reflector. Some rays of light will be thrown from the filament of lamp C and will be reflected at b in substantially the direction indicated toward c; but 90 as the reflecting-prisms are inside the body A there will be a tendency to diffuse the rays, as indicated at a² b² b³ c², Fig. 3. The same will be true of rays which reach other parts of the reflecting-surface, as at d e f. 95

Instead of arranging the cluster of lights below the end of reflector A these can be arranged near the upper part thereof, as at D D. In such case a small reflector E is preferably arranged above each lamp D. Some of the 100 light-rays from the lamp D will then reach the reflector A by direct radiation—say on the line h i—and be reflected toward k, and some rays will be reflected by reflector E to the reflector A and thence reflected and radiated, (see line 105 l m n o, Fig. 2.)

The reflector A may be used with a single lamp, as well as with a cluster. Thus lamp H, Fig. 2, will cast some rays in the direction p q, and such rays will be directed in the general direction r, Fig. 2.

The reflector A illustrated is in the form of

a frustum of a conical body drawn in toward its central portion. This is not a necessary, although a preferred, form of construction. The essential idea of my invention is that the reflecting-prisms B shall be on the interior surface of the reflector and that the reflected rays shall be directed outwardly from the circumference of the reflector.

What I claim is—

- 10 1. The combination with an artificial light outside the reflector, of a reflector of prismatic glass in form of a frustum, having reflecting-prisms on its interior surface, and having its flared end overhanging the light.
- 15 2. The combination with a cluster of electric lamps, of a reflector in form of a frustum surrounding a common center of the cluster, said reflector being composed of glass with a

smooth outer surface, and having reflecting-prisms on its inner surface, the flared edge of the reflector overhanging the lamps.

3. The combination with a main reflector composed of glass, smooth on its outer surface and having reflecting-prisms on its inner surface, the body of said reflector being in form of a frustum flared outwardly and upwardly, of a suspended lamp outside said reflector, and a small reflector near the lamp, and arranged to reflect light-rays from said lamp to the main reflector.

In testimony whereof I affix my signature in presence of two witnesses.

OTIS A. MYGATT.
